Tues. 1573

George B. Owen, of New York, N. Y.
Letters Patent No. 1573 dated May 6, 1862,

The schedule referred to in these Letters Patent and making part of the same.

To all whom it may concern:

Be it known that I, George B. Owen, of the City of New York, have invented or produced a new and original Design for Clock Case, and I do hereby declare that the following is a full, clear and exact description of the same, reference being had to the accompanying drawings making a part of this specification, in which

Figure 1. is a face or front view of a clock case, constructed according to my design.

Figure 2. a side view of the same.

Similar letters of reference indicate corresponding parts in the two Figures.

A. represents the base of the clock case which is of quadrilateral form and has a cylindrical projection B. at its two front corners, the front C. of the base between the two projections B. B. and the sides D. back of them, being plane surfaces. The top of the base has an inclined surface E. all around it, with the exception of its back side, and on the base the body C. of the case is placed, the lower end of the latter at its front and sides being even with the inner edge of the inclined surface E. The body C. of the case is of quadrilateral form and its front corners are chamfered so as to form plane surfaces F. F. on which

there are finion shaped projections e. e. and at the lower parts of said surfaces d. d. there are rectangular projections f. f. having pyramidal caps g. g. and the front side of each projection f. has a semi cylindrical projection h. provided with a conical top i.

The projections f. h. rest on small circular bases j. the edges of which are rounded and are directly above the inclined surfaces of the cylindrical projections B. B. of the base A. The upper part of the body C. at the tops of the plane surfaces d. d. is of cyma recta form, as shown at e. e. and the front of the case designated by a. is sunk slightly inward so as to form a shallow recess.

D. is the cap of the body C. of the case which is formed of a quirked scotia k. which has a cyma recta l. above it surrounded by an ovoli m. These moldings extend around the sides of the case as shown in Figure 2.

The lower part of the front a. of the body C. of the case has two projections n. n. the sides of which o. are parallel with other, and the bottoms p. at right angles with the sides. The tops q. of these projections are of concave form, while the edges all around are made concave forming a scotia r.

Having thus described my invention what I claim as new and desire to secure by Letters Patent, is

The general configuration of the parts herein shown and described, to form a new and original Design for a Clock Case.
